DECORATIVE ILLUMINATED DEVICE

Abraham Abramson, New York, N. Y., assignor to
 Raylite Electric Corp., Long Island City, N. Y.,
 a corporation of New York

Application June 9, 1945, Serial No. 598,569

7 Claims. (Cl. 240—10)

1

This invention relates to improvements in illuminated devices, and more particularly is directed to devices of the character described which provides continuous unbroken streams of flowing vapor in a body of transparent liquid embodied in the operation and construction of illuminated ornamental and decorative display devices such as for Christmas tree lighting, signs and the like.

Among the objects of the invention is to generally improve devices of the character described in which a simplified construction of few and easily assembled parts are required, which shall be economical to manufacture especially in quantity production, which shall be positive and reliable in operation requiring a minimum of external heat supply, and which shall be practical and efficient to a high degree in use.

Other objects of the invention will in part be obvious and in part hereinafter pointed out.

The invention accordingly consists of features of construction, combinations of elements, arrangement of parts which will be exemplified in the constructions hereinafter described and of which the scope of the application will indicate in the following claims.

In the accompanying drawing in which possible illustrative embodiments of the invention are shown

Fig. 1 is a front elevational view partly broken away to expose the interior, showing a unit of a Christmas tree lighting outfit constructed to embody the invention.

Fig. 2 is an enlarged detailed fragmentary view of the integral vapor current generating means as shown in Fig. 1, and

Figs. 3 and 4 are similar views to Fig. 2 showing two modified constructions of vapor current generating means embodying the invention.

Heretofore devices used for purposes similar to that for which applicant's is utilized, have as their principal feature the generation of illuminated vapor bubbles passing in individual spaced succession through a liquid column. In the present invention improved devices of most simple construction are made available which differ from the prior art in providing for the generation of illuminated currents or unbroken streams of vapor extending as waving bands through a liquid column, a plurality of such currents forming in appearance interlaced or entwined fluttering ribbons in activated dancing array to produce a contrasting attractive and novel lighting effect passing through the liquid column.

To this end, as seen in the drawing, there is provided an improved ornamental illuminated

device 10 constructed to embody the invention which is seen to include a vertically disposed transparent tube body of glass or other translucent material designated generally as 11 having an integral closed bottom end 11a and sealed top end 11b, said tube body 11 for the purposes of forming a Christmas tree lighting ornament may be made in appearance to simulate in outline, form, shape and size that of a candle.

10 In one form of the invention, shown in detail in Fig. 2, the tube bottom end 11a may be moulded or otherwise formed to provide spaced recesses 11c on the interior side thereof. The tube body 11 contains a readily volatilizable liquid 12, such as ether or wood alcohol but preferably a translucent liquid which has a like relatively normal low boiling point but which is non-inflammable. The liquid 12 may be placed in the tube body 11 through the top end 11b thereof before fusing 20 the latter for hermetically sealing the liquid 12 therein at a level short of said top end 11b so as to leave a space 13 above the liquid 12 in the tube body 11. The space 13 above the liquid 12 in the tube body 11 may be evacuated before said tube top end 11b is sealed to permit lowering the boiling point normally required for the liquid 12. Said space 13 constitutes a condensing and heat dissipating means for the device 10.

30 The recesses 11c formed in said lower bottom end 11a, each provides a focal point to serve as a source or beginning for the generation of a continuous current, that is, an unbroken stream 14 of vapor extending upwardly through the liquid column 12 on the application of illuminating heat as for example by an incandescent electric lamp 15 in the manner hereinafter described. If desired, the recesses 11c may be of various shapes and sizes, and irregularly spaced apart so that entwined fluttering ribbons 14 producing a wide range of contrasting attractive lighting effects are made available.

40 In Fig. 1 of the drawing, the invention is shown with the improved ornamental illuminated device 10 having the lower bottom end 11a of the tube body 11 supported in close proximity to the bulb 15a of lamp 15. The latter as here shown is mounted in one of the electric sockets 16 of a Christmas tree lighting outfit of any well understood construction (not shown), by means of a 50 sleeve holder or connector 17 made of fiber, glass, plastic or any other non-combustible material. The lower end 17a of the sleeve holder 17 fits snugly over the lamp bulb 15a and the upper end 17b fits snugly over the lower bottom tube body end 11a so that said holder 17 provides a relatively

firm interconnection support or rigid coupling. The holder 17 also serves as a conduit to guide or confine the surrounding air heat conducting medium from the lamp bulb 15a to said bottom tube end 11a as is clear for Figs. 1 and 2. Said lower end 11a formed with the internal recesses 11c is thus disposed directly over the source of heat and light which in this instance is the glowing lamp filament 15b.

In practising the invention, assuming the socket 16 in position on a Christmas tree (not shown) or arranged for other decorative display purposes and connected in an electric circuit power supply (not shown) for lighting the lamp 15, heat and light radiated from the lamp filament 15b herein referred to as radiant illuminated heating, is effective to cause the generation of vapor currents with each of the recesses 11c as a focal point when the heat from said lamp filament 15b is maintained to a sufficient degree to generate vapor at a rate to make the flow thereof continuous in an unbroken stream or streams through the liquid column. The portion 11c of the sleeve holder 17 between the lamp bulb 15a and the tube body end 11a serves as a conduit to confine the heat conducting medium therein for producing the aforesaid degree of heat with a minimum heat producing source.

Light beams from lamp filament 15b are projected longitudinally the length of each of said flowing current 14 which forms a waving illuminated band as seen from the exterior of the tube body 11 and shown in Fig. 1. As each of the recesses 11c cause a separate flowing current 14, those currents together appear to either interlace, entwine or emerge into fluttering ribbons thereby forming contrasting attractive activated lighting effects in the liquid column.

The lighting of bulb 15 also illuminates the side wall of the transparent tube body 11 to the top end 11b thereof and imparts the appearance suggestive of a lighted candle.

It has been found that the construction, shape, size, depth and spacing of the recesses 11c are effective to control the cross sectional shape, contour and general fluttering path of the flowing stream or streams of the continuous unbroken currents 14 whereby a relatively large range of composite illuminating activated streamer effects are made available.

The column of volatile liquid 12 within the tube body 11 which is preferably under less than atmospheric pressure because of the evacuated space 13 above the level of the liquid 12, has an external illuminating radiant heat applied, as by means of a suitable heat source, such as the glowing filament 15b of lamp 15, which acts to focus the effect thereof on the portion of the liquid at the tube bottom end 11a at each of the recesses 11c. Heat from said lamp filament 15b is supplied to an effective degree sufficient to generate a vapor streaming current from each of said recesses 11c, flowing in a continuously and unbroken stream up through the liquid body 12. These currents 14 are illuminated by the light from said lamp filament 15b passing through the liquid body 12 so that each of said currents 14 is seen to sparkle in a waving or fluttering ribbon stream suggesting in activity rapid dancing movements. Within a wide range of heat supplied such movements can be made to appear more or less active as desired. Each of the various recesses 11c generates an individual current 14, as above described which may be located so as to interlace, entwine or merge thereby forming in-

tricately contrasting and attractive lighting effects.

The vapor forming currents 14 on reaching the space 13 after passing through the liquid column 12 condense and disappear. The condensed vapors return to the liquid in body 11 for replenishing the same to continue the cycle of operations above described as long as said illuminating radiant heat from lamp filament 15b is applied.

In Fig. 3 a modified detailed construction of the invention is shown in which there is provided bottom end 21a of a tube body 21. Here instead of providing recesses 11c as in bottom tube end 11a shown in Figs. 1 and 2, spaced protuberances 21c of the same or irregular formation are integral molded or formed to project up from the interior walls of said bottom tube end 21a. Each of said protuberance 21c serves as a focal point or generating source of a continuous stream of unbroken current 24 similar in all respects to the continuous flow of currents 14 in the device 10 as described above.

In Fig. 4 still another modified detailed construction embodying the invention is shown in the form of bottom end 31 of a tube body 31 which instead of providing recesses 11c as in tube end 11a shown in Figs. 1 and 2, or a protuberance 21c in tube end 21 as shown in Fig. 3, the interior side of bottom tube wall 31a is resurfaced by etching, sandblasting, molding or otherwise to provide a roughened or patched surface or spaced surfaces 31c which serve as focal points or sources for generating continuous streams of unbroken currents 34 similar in all respects to flowing currents 14 and 24 described above.

While in the above described manner of operation a continuous unbroken stream current of flowing vapor is produced in the liquid body, the novel construction may also be utilized for producing a flow of bubbles in a stream by applying insufficient heat to form said continuous stream current from the various focal points.

It is to be understood that the modified constructions shown in Figs. 3 and 4 may be assembled in holders 17 and supportingly mounted on incandescent lamp 15 in the same manner as have been described for device 10. The manner of operation described for device 10 above is equally applicable to said modified forms in practising the invention.

It is therefore seen that there is provided an improved device in which the objects of the invention are achieved and which are well adapted to meet all conditions of practical use.

As various possible embodiments may be made in the above invention for use for different purposes and as various changes might be made in the embodiments above set forth, it is understood that all the above matters here set forth or shown in the accompanying drawing are to be interpreted as illustrative and not in a limiting sense.

Thus having described my invention, I claim as new and desire to secure by Letters Patent:

1. A device of the character described comprising a sealed transparent body, a volatile liquid partially filling said body, the unfilled portion of said body being under reduced atmospheric pressure, means incorporated in the interior wall of said body immersed in the liquid to provide a focal point serving as a source for generating an unbroken current of vapor for passing through the liquid to produce an activated light effect and a heating and illuminating means of suffi-

cient heating capacity to produce said generated vapor current light effect positioned adjacent said first mentioned means.

2. A device of the character described comprising a sealed transparent body, a volatile liquid partially filling said body, means incorporated in the interior wall of said body immersed in the liquid to provide a focal point serving as a source for generating an unbroken current of vapor for passing through the liquid to produce an activated light effect, and a heating and illuminating means of sufficient heating capacity to produce said generated vapor current light effect positioned adjacent said first mentioned means.

3. The device defined in claim 2 in which said first mentioned means includes a plurality of spaced focal points integrally formed with said interior of wall to serve as corresponding plurality of said generating sources.

4. The device defined in claim 2 in which said first mentioned means comprises a protuberance

extending to upstand from said interior wall and position in the path of illuminated heating beams radiating from said last mentioned means.

5. The device defined in claim 2 in which said first mentioned means comprises a recess extending into said interior wall and positioned in the path of illuminated heating beams radiating from said last mentioned means.

10 6. The device defined in claim 2 in which said first mentioned means comprises a roughened portion on said interior wall and positioned in the path of illuminated heating beams radiating from said last mentioned means.

7. The device defined in claim 2 in which said last mentioned means comprises an incandescent lamp, and which includes a supporting holder for coupling the lamp to said transparent body, said holder confining the radiant heat passing from the incandescent lamp to concentrate on said focal point.

ABRAHAM ABRAMSON.
